(57) **CLAIM**

We claim the ornamental design for a lapboard with combined keyboard, as shown and described.

DESCRIPTION

FIG. 1 is a top view of the lapboard with combined keyboard in an open position;

FIG. 2 is a bottom view thereof;

FIG. 3 is a front view thereof;

FIG. 4 is a left-side view thereof;

FIG. 5 is a front view thereof in a closed position;

FIG. 6 is a top view thereof;

FIG. 7 is a bottom view thereof;

FIG. 8 is a left-side view thereof; and,

FIG. 9 is a right-side view thereof.
